Dec. 1432

Levi L. Tower, of Boston, Mass.
Assignor to Butter, Tower & Co. of same place.
Whole No. 1432. Letters Patent No 67-dated June 11, 1861.

The schedule referred to in these Letters Patent and making part of the same,
To all persons to whom these presents shall come:

Be it known that I, Levi L. Tower,
of Cambridgeport, in the County of Middlesex, and State of Massachusetts,
have invented or produced a new and ornamental design for a trade mark
to be applied to Lead Pencils &c. and I do hereby declare the same to be fully
set forth in the following specification, and represented in the accompanying drawing, which
depicts an elevation of a lead pencil having my design applied thereto, —

The said design consists of two stars (each having five points on its
periphery) one of which is placed immediately before the word "STAR," and the other immedi-
ately after such word. There is also a fillet or band extending from and connecting the
two highest points of each star, as well as another fillet or band which connects the two
lowest points of each star, the whole being as shown in the drawing.

The said design is intended to be stamped, upon a lead pencil,
or printed and applied thereto, as circumstances may require.

I claim the said design as a trade mark, to be applied to lead
pencils &c. the same being described and represented.
